Filed Jan. 5, 1961, Ser. No. 63,452

Term of patent 14 years

(Cl. D26—14)

FIG. 1 is a front end elevational view of a diaphragm housing for a loud speaker or the like embodying my new design;

FIG. 2 is a side elevation of the diaphragm housing;

FIG. 3 is a vertical sectional view taken generally along the plane of line 3-3 of FIG. 1, looking in the direction of the arrows;

FIG. 4 is a sectional view taken along the plane of line 4-4 of FIG. 1 looking in the direction of the arrows.

The essential features of the design reside in the portions shown in full lines.

I claim:

The ornamental design for a diaphragm housing for a loud speaker or the like, substantially as shown and described.
